LOUIS W. THOMPSON, OF SCHENECTADY, NEW YORK, ASSIGNOR TO GENERAL ELECTRIC COMPANY, A CORPORATION OF NEW YORK

ELECTRIC REGULATING SYSTEM

Application filed October 8, 1923. Serial No. 667,067.

5 My invention relates to electromagnetic devices and electric regulating systems and particularly to such systems which comprise a control magnet having a solenoid connected so as to be energized in accordance with the condition to be regulated, and a core adapted to be actuated by said solenoid to control the regulating means.

10 An object of my invention is to provide an improved construction of control magnet whereby the desired pull characteristic of the magnet may be obtained over an extended range of movement of the core of the magnet and whereby the desired regulation may be secured throughout the entire range of movement.

15 Another object of my invention is to provide an improved construction of the controlling magnet whereby the setting of the magnet may be readily varied.

20 My invention will be better understood from the following description taken in connection with the accompanying drawings, and its scope will be pointed out in the appended claims.

25 In the accompanying drawings, Fig. 1 shows one embodiment of my invention; Fig. 2 shows a modification of the embodiment shown in Fig. 1, and Fig. 3 shows another embodiment of one feature of my invention.

30 Referring to Fig. 1, 1 represents an alternating current circuit which is supplied from a source 2 and which, it will be assumed, supplies a load, not shown, requiring a constant voltage to be impressed thereon in order to function properly. For controlling the voltage of the circuit 1, sections of a resistor 3 are arranged to be connected in series with circuit 1 by means of a magnet 4, which actuates a curved arm 5 so that it rolls over the contacts 6 which are connected to different points of the resistor. Any suitable means such as a cup 7 containing mercury and a 35 movable contact 8 connected to the movable arm 5 may be provided for maintaining an electrical connection to the curved arm 5 as it moves over the contacts 6. While I have shown the preferred arrangement for maintaining an electrical connection to the arm

which is actuated by the core, it is evident that an ordinary pigtail connection, as shown in Fig. 3, may be used if desired.

35 The magnet 4 which actuates the arm 5 comprises a solenoid 9 connected across the circuit 1 so as to be responsive to the voltage thereof, and a core 10 extending within the solenoid and arranged to float in the region of maximum pull in its normal operating position. The core 10 is directly connected to the arm 5 by means of a stem 11 secured to the core and a light stiff flat member 12 one end of which is pivotally secured to the stem 11 and the other end of which is fastened to the contact arm 5. By means of the construction shown, the contact arm 5 can be readily removed from the contacts 6 so that they can be cleaned. The solenoid 9 is wound on a non-magnetic spool and so mounted as to have an unconfined external magnetic field.

40 It will be observed that as the contact arm 5 moves over the contacts 6 the weight of the contact arm varies the force required to be exerted on the core to move the arm. When the arm 5 is in the position shown, the center of gravity of the arm is substantially above the middle contact, about which the arm rotates at this time, and therefore the solenoid has to exert a force only sufficient to move the core in order to move the contact arm 5. When, however, the contact arm 5 is in engagement with the contacts to the right of the middle contact, the center of gravity of the arm is to the left of the point about which the arm is rotating so that the weight of the contact arm 5 tends to lift the core 10. When the arm 5 is in engagement with the contacts to the left of the middle contact, the center of gravity of the arm is to the right of the point about which the arm is rotating so that the weight of the contact arm tends to push the core 10 down. Therefore, in order for the regulator to maintain a constant voltage across the circuit 1, means must be provided to compensate for the variations in the force required to move the core due to the weight of the arm 5 as it moves over the contacts so that a given current through the solenoid can

maintain the core at any point in its range of movement.

Furthermore it is evident that it is desirable that the core should have as great a movement as possible for a given change in current through the solenoid when the voltage changes so that very sensitive regulation may be obtained.

For accomplishing these desired results a magnetic member 13, preferably of soft iron, is placed below the lower end of the core 10 and another magnetic member 14, preferably of soft iron, is placed above the upper end of the core. These magnetic members may be held in place by any suitable means such as the brackets 15 and 16, respectively, which are fastened to the support 18 of the solenoid 9. Preferably, the bracket 16 is made of magnetic material and the bracket 15 is made of non-magnetic material. The stem 11 extends through an opening in the magnetic member 14 so that the member acts as a guide for the stem. Also a rod 17, which is secured to the bracket 15 and which extends up into a hole in the bottom of the core, helps to guide and steady the core.

The magnetic members 13 and 14 operate in the following manner to produce the desired results. As the voltage across the circuit 1 tends to decrease, the core 10 drops down so that the contact arm 5 successively engages the contacts 6 to the right of the middle contact thereby decreasing the number of sections of resistance in series with the circuit 1. Since the weight of the arm 5 tends to lift the core under these conditions it does not take so much current through the solenoid to exert the necessary pull on the core to maintain it in a given position as it would if only the solenoid were lifting the core. Therefore the regulator tends to undercompound. As the core 10 drops, however, the air gap between the magnetic member 13 and the core decreases so that the reluctance of the path of the leakage flux through these parts is decreased. Consequently there is a stronger pull between the core and the magnetic member 13 which tends to move the core down farther and thereby increase its travel for a given change in current in the solenoid. The magnetic member 13 is so arranged that this increase in pull compensates for the upward force produced by the weight of arm 5 as well as the change in the pull of the solenoid due to the change in the position of the solenoid so that with normal voltage across the circuit 1, the force exerted on the core by the solenoid is just sufficient at any point in the path of movement of the core to maintain the contact arm in engagement with any one of the contacts 6 to the right of the middle contact.

When the voltage of the circuit 1 tends to increase, the core 10 moves up and the movable arm 5 rolls over the contacts 6 to the

left of the middle contact so that more sections of the resistance 6 are connected in series with the circuit 1, and the weight of the arm 5 tends to push the core 10 down. Under these conditions the magnet 4 tends to overcompound as the solenoid has to exert more force to hold the core in a given position. As the core 10 rises in the solenoid, however, the air gap between the top of the core and the magnetic member 14 decreases so that the pull between the core and the member increases and moves the core up farther so that the travel of the core is increased. The magnetic member 14 is so arranged that the increase in pull between the member 14 and the core compensates for the force exerted by weight of the arm 5, as well as the change in the pull of the solenoid due to the change in the position of the core in the solenoid so that with normal voltages across the circuit 1, the force exerted on the core by the solenoid is just sufficient at any point in the path of movement of the core to maintain the contact arm in engagement with any one of the contacts to the left of the middle contact.

It will, therefore, be observed that by means of the magnetic members 13 and 14 a given current through said solenoid will maintain the core at any point in its range of movement notwithstanding the varying force exerted thereon by the arm as it rolls over the contacts 6. Consequently the regulator will maintain an almost absolutely constant voltage throughout its range of regulation. Also, the magnetic members effect a greater movement of the core for a given change in voltage than if there were no magnetic members provided.

Furthermore it is evident that if the regulator were arranged so as to operate only over a portion of the contacts shown, such for example as only the contacts to the right or to the left of the middle contact, one of the magnetic members 13 and 14 could be omitted.

In order to change the setting of the magnet 4 so that it will operate to maintain the voltage of the circuit 1 constant at different values I provide an adjustable short circuited winding 19, which is shown as an adjustable ring, preferably of copper, around the core. This short circuited winding is preferably adapted to be secured to the core in any suitable manner such as a screw 20 which extends through the short circuited ring and engages the core.

It will be observed that when the ring is moved so that it is cut by more of the flux produced in the core by the solenoid, the ring is more strongly repelled by the solenoid and also the reluctance of the magnetic circuit of the magnet is increased so that it takes a higher voltage to maintain the core in a given position. Therefore the voltage, which the regulator maintains constant, may be readily changed by merely changing the posi-

tion of the short circuited coil relative to the core.

While it is preferable to secure the ring to the core so as to obtain both the repelling action and change in the reluctance, it is evident that the ring could be adjustably secured to the bracket 15 as shown in Fig. 2. With such an arrangement, however, the repelling force on the ring has no effect upon the setting 10 of the magnet.

It is evident that the magnetic members may be used on both alternating and direct current magnets to accomplish the desired results whereas the adjustable short circuited 15 winding will be effective only on alternating current magnets.

While I have shown the preferred embodiment of my invention in which the two magnetic members perform the double function 20 of compensating for the effect of weight of the arm actuated by the core of the magnet and of increasing the movement of the core for a given change in current through the solenoid, I desire it to be understood that my 25 invention is not limited to the use of the magnetic members for accomplishing this double function as I find that they may be used merely to increase the movement of the core for a given change in the current through 30 the solenoid. This feature of my invention, for example, may be embodied in a contact-making voltmeter, such as shown in Fig. 3, in which the core actuates a pivoted arm 12' carrying a contact 21 which is adapted to engage the stationary contacts 22 and 23. As 35 is well known in the art, it is desirable that contacts 22 and 23 should be far enough apart so that movable contact 21 can disengage one 40 of the stationary contacts before it engages the other and at the same time it is desirable that this movement should be effected in response to a very small variation in voltage if close regulation is required. I find that by 45 placing magnetic members above and below the core the desired movement of the core and the desired sensitiveness can be obtained.

While I have shown and described several 50 embodiments of my invention, I do not desire to be limited thereto but seek to cover in the appended claims all those modifications which fall within the true spirit and scope of my invention.

What I claim as new and desire to secure by Letters Patent of the United States, is,—

1. An electromagnet comprising a solenoid having a substantially unconfined external magnetic field, a core extending within said solenoid and arranged to float in normal operation with its entering end within the region of maximum pull, a magnetic member in spaced relation with one end of said core for modifying the pull on said core, and non-magnetic means for supporting said magnetic member.

2. An electromagnet comprising a solenoid

having a substantially unconfined external magnetic field, a core extending within said solenoid and arranged to float in normal operation with its entering end within the region of maximum pull, and magnetic members positioned in spaced relation with each end of said core for modifying the pull on said core, one of said magnetic members being arranged to assist and the other to oppose the pull of said solenoid on said core.

3. An electromagnetic device comprising a movable control element requiring a different operating force in different operating positions, a core operatively connected to said control element, a solenoid adapted to actuate said core, and a magnetic member in the magnetic field produced by said solenoid operative to produce a change in the force exerted on said core as the position of said core changes so as to compensate for the variations in the force required to actuate said control element.

4. An electromagnetic device comprising a movable arm having a shifting fulcrum, a core operatively connected to said arm so that the weight of said arm as its fulcrum shifts changes the amount of force that has to be applied to said core to move said arm, a solenoid adapted to actuate said core, and a magnetic member arranged adjacent each end of said core so that one assists the pull of said solenoid on said core and the other opposes the pull of said solenoid on said core, said magnetic members being so positioned with respect to the core that as the position of the core changes to move said arm the forces exerted by said members compensate for the variations in the force produced by the weight of said arm.

5. A magnet comprising a solenoid, a core extending within said solenoid and adapted to be maintained by a given energization of said solenoid in a plurality of positions intermediate the limits of predetermined range of movement, a movable arm actuated by said core and arranged so that the force required to move said arm varies with the position of the core, and a magnetic member arranged adjacent to one end of said core and operative as the position of said core changes to compensate for the variations in the force produced by the movement of said arm.

6. A magnet comprising a solenoid, a core extending within said solenoid and adapted to be maintained by a given energization of said solenoid in a plurality of positions intermediate the limits of a predetermined range of movement, a movable arm actuated by said core and arranged so that the force required to move said arm varies with the position of the core, a magnetic member arranged adjacent to one end of said core, and a second magnetic member arranged adjacent to the other end of said core, said magnetic members being so arranged with respect to the

core that as the position of said core changes the forces exerted by said members compensate for the variations in the force produced by the movement of said arm.

5 7. A magnet comprising a solenoid, a core, a movable arm actuated by said core and arranged so that the force required to move said arm varies with the position of the core, and a magnetic member arranged in the magnetic field produced by said solenoid, said 10 magnetic member being arranged to change the pull exerted on said core by said solenoid so that a given current through said solenoid maintains said arm at any point in its range 15 of movement.

8. A magnet comprising a solenoid, a core, a movable arm actuated by said core and arranged so that the force required to move said arm varies with the position of the core, and 20 a magnetic member arranged adjacent each end of said core so that as the core moves the change in air gaps between the core and the magnetic members varies the reluctance of the magnetic circuit of the magnet in such 25 a manner that a given current through said solenoid is arranged to maintain said arm at any point in its range of movement.

9. In a regulating system, a magnet comprising a solenoid connected to be responsive 30 to the condition to be regulated, a core arranged to be actuated by said solenoid, a movable arm actuated by said core and arranged so that the force required to move said arm varies with the position of the core, 35 and magnetic means operative to produce a change in the pull exerted on said core as the position of said core changes so as to compensate for the variations in the pull required to move said arm.

40 10. In a regulating system, a magnet comprising a solenoid connected to be responsive to the condition to be regulated, a core arranged to be actuated by said solenoid, a movable arm actuated by said core and arranged so that the force required to move said arm varies with the position of the core, and 45 a magnetic member arranged adjacent to one end of said core said magnetic member being arranged to change the pull exerted on said 50 core as the position of said core changes so as to compensate for the variations in the pull required to move said arm.

11. In alternating current device comprising a solenoid, a core adapted to be attracted by said solenoid, an adjustable short circuited winding surrounding said core whereby the energization of the magnet required to hold the core in any position may be varied.

55 12. An alternating current device comprising a solenoid, a core adapted to be attracted by said solenoid, a ring of conducting material surrounding said core and means for securing said ring to said core in various positions of adjustment to vary the setting of the magnet.

13. An alternating current magnet comprising a solenoid, a core adapted to be actuated by said solenoid, a movable arm actuated by said core and arranged so that the force required to move said arm varies with the position of the core, a magnetic member arranged adjacent to one end of said core and operative as the position of said core changes to compensate for the variations in the force produced by the movement of said arm, and an adjustable short circuited winding surrounding said core whereby the energization of the magnet required to hold the core in any position may be varied.

70 In witness whereof, I have hereunto set my 80 hand this 6th day of October, 1923.

LOUIS W. THOMPSON.
